UNITED STATES PATENT OFFICE.

JAMES W. MULLINGS, OF WASHINGTON, DISTRICT OF COLUMBIA.

DESIGN FOR AN ADVERTISING SIGN.

Application filed July 31, 1923. Serial No. 6,905. Term of patent 3½ years.

To all whom it may concern:

Be it known that I, JAMES W. MULLINGS, a citizen of the United States, residing at Washington, in the District of Columbia, have invented a new, original, and ornamental Design for an Advertising Sign, of which the following is a specification, reference being had to the accompanying drawing, forming part thereof.

The figure is a plan view of an advertising sign, showing my new design.

I claim:

The ornamental design for an advertising sign, as shown.

JAMES W. MULLINGS.
